(No Model.)

E. J. WOOD.

HEATING APPARATUS FOR DRYING HOUSES.

No. 245,911.

Patented Aug. 16, 1881.

UNITED STATES PATENT OFFICE.

EDGAR J. WOOD, OF BROOKLYN, NEW YORK.

HEATING APPARATUS FOR DRYING-HOUSES.

SPECIFICATION forming part of Letters Patent No. 245,911, dated August 16, 1881.

Application filed June 16, 1881. (No model.)

To all whom it may concern:

Be it known that I, EDGAR J. WOOD, of Brooklyn, in the county of Kings and State of New York, have invented certain new and useful Improvements in Heating Apparatus for Drying-Rooms or Drying-Houses for Lumber, of which the following is a specification.

My invention relates to drying rooms or houses for lumber in which air is circulated through the room or house by means of a blower and is heated by contact with suitably-arranged radiators, through which superheated steam is passed.

The invention consists in certain novel features in the arrangement of the radiators for heating the air, and in a novel construction of the air-flues or passages, whereby the distribution of air is regulated.

The invention also consists in various details of construction, hereinafter fully described.

In the accompanying drawings, Figure 1 represents a plan and horizontal section of a drying house or room and appurtenances embodying my invention. Fig. 2 represents a vertical longitudinal section thereof upon the dotted line *xx*, Fig. 1. Fig. 3 represents a vertical transverse section upon the dotted line *yy*, Fig. 2; and Fig. 4 is a sectional elevation of the condenser in a modified form.

Similar letters of reference designate corresponding parts in all the figures.

A designates a drying-room or drying-house, composed of four walls of brick or other material roofed over, and about midway of the height of said room or house is a tier of beams, *A'*, forming a rack, upon which lumber may be laid.

Upon the floor of the room or house *A* is a steam-radiator, *B*, the pipes of which extend back and forth for the whole width and length of the room or house, as best seen in Fig. 1.

In the end of the room or house are two chambers or inclosures, *C C'*, or they might otherwise be called a "single chamber," divided by a partition, *C²*, as seen in Fig. 3, and communicating with each other over the top of said partition. As here shown, said chambers *C C'* only extend upward to the rack *A'*, and they are separated or divided from the main portion of the room or house. Arranged in said chambers *C C'* are two radiators, *D D'*,

here shown as composed of connected parallel tubes, as best seen in Fig. 3.

It is very desirable, in order to make the steam to supply the radiators *B D D'* as effective as possible, that it should be superheated, and I have represented a superheater, *E*, which may be heated by a furnace below it, and of any suitable construction, as may be found most desirable, and steam is conducted from any suitable and adjacent boiler to the superheater through a pipe, *a*, as shown in Fig. 1, under control of a valve, *a'*, therein. From the superheater *E* the superheated steam passes through a pipe, *b*, to one end of the radiator *B*, under control of a proper valve, *b'*, (best shown in Fig. 1,) and from the opposite end of said radiator the water of condensation passes to the boiler or the trap through a pipe, *c*, as seen in Fig. 1.

Steam is supplied to the two radiators *D D'* by means of pipes *c'* and *d*, under control of valves, and as clearly shown in Fig. 1, and the condensed water is exhausted therefrom through a pipe, *d'*, (shown in Fig. 3,) to a boiler or a trap, (not here shown.)

I will now proceed to describe the course of the air in passing through the drying room or house.

F designates the blower, by which air is withdrawn from the upper part of the room or house, and from which the outflow of air is conducted into the lower part thereof. The suction-pipe *G* of the blower *F* extends upward therefrom and along the upper part of the dry room or house, upon one side thereof, and the discharge-pipe *H* from said blower terminates in the chamber *C*, as best shown in Figs. 2 and 3.

The suction-pipe *G* of the blower, whereby air is withdrawn from the top of the drying room or house, is provided with numerous inlets *e*, which may be provided with dampers or valves, whereby the quantity of air drawn from any part of the room or house may be conveniently regulated.

The air delivered into the chamber *C* from the discharge-pipe *H* passes from said chamber over the partition *C²* into the chamber *C'*, and in its passage is heated by the radiators *D D'*, after which said air passes from the chamber *C'* into a horizontal pipe or trunk, *I*,

which extends lengthwise of the drying room or chamber, in the lower part thereof, and on the opposite side from the air-suction pipe G, as shown clearly in Fig. 1. The pipe or trunk I has its upper part composed of hinged sections $f f' f'' f'''$, which may, any one or all of them, be raised or opened to permit the passage of air into the room or house at any desired point below the radiator B, whence the air passes upward through and in contact with the pipes of the radiator, and is thereby further heated.

It is desirable that the air employed in drying be freed as far as possible from moisture, and to enable this to be done I employ a condenser, J, here shown as consisting of a simple box or chest having arranged within it a coil or series of cold-air pipes, of which J' is the inlet-pipe and J^2 is the outlet pipe or flue. The outlet-pipe J^2 is prolonged upward above the condenser, and into it extends a branch pipe, K, leading from the furnace, which heats the superheater E, as previously described. The ascending current of the hot air and products of combustion, passing from the furnace of the superheater E, and thence through the branch pipe K and outlet pipe or flue J^2 , produce a constant flow of air from the coil or pipes of the condenser and a constant flow of cold air through the same, which cold air enters at the inlet J' . The body or shell of the condenser J is connected by a pipe, L, with the suction-pipe G of the blower F, and by a pipe, E, with the discharge-pipe H from the blower, and while the main or larger portion of the air is kept circulating through the blower F and its suction and discharge pipes G and H, a smaller proportion or quantity thereof is kept circulating through the pipes L L' and condenser J, whereby it is rid of its moisture, thus maintaining a uniform humidity of the air used in drying. The pipes L L' are provided with suitable gates or valves for regulating the flow of air through them.

If water were used as a condensing agent in 45 the condenser J, the air would pass through the pipes or coils of the condenser, instead of through the condenser around said pipes or coils.

By my invention I provide for properly regulating the supply of heated air to all parts of the dry room or house, and also for ridding the air used in drying, as far as is possible, from its moisture.

In the condenser shown in Fig. 4 the air 55 passes through a pipe surrounded by water in the body of the condenser. In case it should be found desirable to introduce a small quantity of steam into direct contact with the lumber in the drying room or house, I may employ 60 pipes s, arranged above the radiator B and supplied with steam from the superheater E. The pipes s may be perforated, if required.

What I claim as my invention, and desire to secure by Letters Patent, is—

1. The combination, with the drying room or house A, of the radiators B D D', arranged substantially as herein described, and the superheater for supplying superheated steam to said radiators.

2. The combination of the room or house A, the chambers C C', separated by a partition, C², the radiators D D', arranged in said chambers, the blower F, the suction-pipe G, the discharge-pipe H, leading to the chamber C, and the air-trunk I, leading from the chamber C', and provided with gates or valves along its length, all substantially as specified.

3. The combination of the condenser J, having an air-inlet, J', and an air-outlet, J², the superheater E, heated by a furnace, and the escape pipe or flue K, leading from said furnace to the outlet J², substantially as specified.

EDGAR J. WOOD.
